Des. 188,648
Patented Aug. 16, 1960

188,648

HARD SURFACE FLOOR COVERING OR SIMILAR ARTICLE

Harvey G. Cohen, Bloomfield, and William Currie,
Kearny, N.J., assignors to Congoleum-Nairn Inc.,
Kearny, N.J., a corporation of New York

Filed Mar. 15, 1960, Ser. No. 59,745

Term of patent 14 years

(Cl. D92—17)

The figure is a plan view of a hard surface floor covering, showing our new design.

A unit is enclosed within the broken lines on the drawing, which unit is repeated in regular succession as indicated by the extension beyond the unit boundaries.

We claim:

The ornamental design for a hard surface floor covering or similar article, substantially as shown and described.
